Ralph C. Osborn, Bloomington, Ill.

Application July 2, 1953, Serial No. 25,766

Term of patent 14 years

(Cl. D9—2)

To all whom it may concern:

Be it known that I, Ralph C. Osborn, a citizen of the United States and a resident of Bloomington in the county of McLean and State of Illinois, have invented a new, original, and ornamental Design for a Vacuum Cleaner With Accessory Ring, of which the following is a specification, reference being had to the accompanying drawings, forming part thereof.

Fig. 1 is a top and front perspective;

Fig. 2 is a rear elevation view of a vacuum cleaner with accessory ring, showing my new design.

I claim:

The ornamental design for a vacuum cleaner with accessory ring, substantially as shown.

RALPH C. OSBORN.
